UNITED STATES PATENT OFFICE.

LLOYD W. BUCHENAU, OF STOCKTON, CALIFORNIA.

DESIGN FOR A GUM AND MINT CASE.

52,558.

Specification for Design.

Patented Oct. 15, 1918.

Application filed January 16, 1918. Serial No. 212,144. Term of patent 14 years.

To all whom it may concern:

Be it known that I, LLOYD W. BUCHENAU, a citizen of the United States, residing at Stockton, in the county of San Joaquin, State of California, have invented a new, original, and ornamental Design for a Gum and Mint Case, of which the following is a specification, reference being had to the accompanying drawings, forming a part hereof.

In the drawings, Figure 1 is a side view of a gum and mint case, showing my new design.

Fig. 2 is a plan view of the same.

I claim:

The ornamental design for a gum and mint case, as shown.

LLOYD W. BUCHENAU.
